UNITED STATES PATENT OFFICE.

ALFRED G. HEGGEM, OF TULSA, OKLAHOMA, ASSIGNOR TO THE OIL WELL IMPROVEMENTS COMPANY, OF TULSA, OKLAHOMA.

CASING-HEAD.

1,165,253.

Specification of Letters Patent. Patented Dec. 21, 1915.

Application filed August 17, 1914. Serial No. 857,118.

To all whom it may concern:

Be it known that I, ALFRED G. HEGGEM, a citizen of the United States, residing at Tulsa, in the county of Tulsa and State of Oklahoma, have invented certain new and useful Improvements in Casing-Heads; of which the following is a specification.

My invention relates to the construction of casing heads for oil, gas or other wells, and is designed to afford a simple, durable and efficient device by which the flow of oil, gas, water, or other fluid from a well may be constantly maintained under control.

As is well understood, oil flowing from a well is carried by gas and moves at a high velocity. In casing heads as now constructed the oil, in having its direction of flow changed so as to permit it to issue from the usual side opening in the casing head, impinges upon surfaces that very greatly interfere with the flow, the stream of oil being to a considerable extent broken up into particles, rebounding and interfering with the upwardly rising column of oil. This atomizing or nebulizing of the oil is the cause of the blue, smoke-like oil vapor which is observable in flowing wells, the vapor being gas carrying particles of oil. The oil thus nebulized, which frequently amounts to a large number of barrels a day, is often entirely wasted. By my invention substantially all of the oil thus dissipated may be saved without the necessity of employing tanks for catching this vapor and permitting it to settle.

One of the principal objects of my invention; therefore, is to provide a casing head in which atomizing or nebulizing of flowing oil, commonly attendant upon delivering it through a lateral opening in the casing head, is greatly reduced.

If, with present methods of manipulating oil and gas wells, a sudden flow of gas is encountered during drilling and the gas becomes ignited at the surface, there is not sufficient time to permit the drilling tools to be withdrawn from the well and the well rig is almost invariably destroyed by fire, with the attendant danger to life and property. With a casing head involving certain features of my invention this risk to life and property is almost completely eliminated, as the flow of fluid through the well may be

immediately controlled without the necessity of withdrawing the drilling tools.

A further special object of my invention, therefore, is to provide a casing head by which the flow of fluid from the well may be controlled without the necessity of first withdrawing the drilling tools from the well.

Generally stated, the several objects of my invention are embodied in a casing head involving a body having a plurality of passages therein, and a valve member rotatably mounted on said body and serving to control the flow of fluid through the passage, said valve member having a curved deflecting surface which is adapted to suitably change the direction of flow of fluid impinging thereagainst and also having a recess which is adapted to receive a drilling cable when said valve member is rotated to check the flow of fluid.

In the drawings illustrating my invention, the scope whereof is pointed out in the claims, Figure 1 is a vertical sectional view of a casing head embodying my invention; Fig. 2 is a section, taken in the plane of the line 2—2, Fig. 1; Fig. 3 is a horizontal section, taken in the plane of the line 3—3, Fig. 1; and Fig. 4 is a side elevation of the casing head.

The body 1 of the casing head is preferably formed with a side opening or lateral passage 2 and with aligned vertical passages 3 and 4, respectively, the several passages extending inwardly and opening into that portion of the interior of the body which receives the rotatable valve 5. Each of said passages is preferably threaded interiorly, the threads of the passage 2 permitting the attachment of a flow line from the casing head to a flow tank; the threads of the passage 3 permitting any desired pipe connection or the insertion of a plug; and the threads of the passage 4 being designed to receive the well casing. As shown more particularly in Figs. 1 and 2, the upper passage 3 may be counterbored, so as to form an annular shoulder 6 which affords a seat for an ordinary oil saver disk. Set screws 7 may be conveniently employed in maintaining the oil saver disk (not shown) in position when in use.

Rotatably mounted within the body 1 of

the casing head is a valve member 5 which may be turned so as to prevent fluid from flowing upwardly through the passage 4; or which may occupy a position in which the fluid is prevented from flowing through the passage 3 while being permitted to flow through the passage 4 and thence out through the lateral passage 2; or which may occupy the position shown in the drawings, in which the several passages, 2, 3 and 4, are in open communication with each other. In this latter position of the valve 5 it will be seen that the drilling tools may be lowered into the well and drilling operations freely performed.

The valve member 5 is provided upon its interior with a deflecting surface 8 which, when the valve member 5 is in a position closing the passage 3, serves to change the direction of flow of fluid rising through the passage 4 and to deflect it without violent disturbance toward the laterally opening passage 2, thus promoting the flow of the stream of oil toward and into said lateral passage. As shown in the drawings, the deflecting surface 8 is preferably cylindrical and of a radius of curvature corresponding to that of the cylindrical passages 2, 3 and 4, the axis of curvature of said cylindrical deflecting surface extending at an angle to the axis upon which the valve member 5 turns. When operating to perform its function of deflecting the upwardly rising stream of oil, the direction of curvature of the cylindrical surface 8 extends or inclines from the lower passage 4 toward the lateral passage or side opening 2 in the casing head. The rotatable plug valve member 5 is also preferably provided with a recess 9 which is adapted to receive the drilling cable when the valve member is actuated during drilling operations to check the flow of the fluid. This recess is preferably so positioned that its path of travel intersects the coincident axes of the vertical passages 3 and 4 in the body 1, and, as shown, it is also preferably somewhat flared and provided with rounded corners, since by these means the drilling cable may more readily enter said recess when the plug 5 is turned to a position to check the flow of fluid.

The axis of rotation of the plug 5 preferably passes through the lateral passage 2 of the body and coincides with the axis of said passage. The plug is assembled with the body 1 by being introduced through a circular aperture opposite the passage 2 and is retained in such assembled position by means of a stuffing box member 10 that is secured to the body 1 by means of bolts 11, the packing ring 12 of suitable material being preferably interposed between the stuffing box 10 and the body 1 to prevent the escape of fluid between such parts.

65 The rotatable valve member 5 is provided

with an axially arranged stem 13 which projects outwardly through the stuffing box 10. Leakage of fluid between the stuffing box and the valve stem may be conveniently prevented by means of a packing ring 14 which is compressible by a gland or follower 15 that may be secured to the stuffing box 10 by means of cap screws 16, such cap screws, as will hereinafter appear, being preferably so arranged as to serve as stops for determining the proper positions of the valve member 5. The outer end of the stem 13 may be threaded interiorly, as at 17, for the purpose of permitting a joint of pipe to be secured thereto, to thereby form a long stem whereby the valve plug 5 may be operated from a point outside the derrick. Near its outer end the stem 13 is preferably provided with diametrically extending holes 18 which are adapted to receive a bar, section 85 of pipe or similar appliance for turning the valve member 5. The holes 18 in the valve stem and the cap screws 16 which secure the gland 15 in place are preferably so formed and arranged that the said cap screws, by 90 engaging the bar introduced in one of the holes 18 for operating the valve member 5, serve as stops whereby the position of the rotatable valve member may be determined.

The surfaces on the interior of the body member 1 which form bearings for the plug member 5 are preferably comparatively narrow raised ribs having depressions between them. The opening at the inner end of each of the passages of the body is bordered or surrounded by a rib 19 of such character, those ribs which are at the ends of the vertically aligned passages 2 and 3 co-operating with the plug 5 to effectively seal said passages against the flow of fluid through them, and the rib 19 bordering the inner opening of the laterally extending passage 2 serving as a shoulder or stop which, by engaging the ring-like end of the valve plug 5, serves to limit the axial movement of the plug in one direction. The interior surface of the body member 1 of the casing head is also preferably provided with similar circularly extending bearing ribs 20 which respectively engage the end portions of the plug 5. 115

I claim:

1. A casing head involving a body provided with means whereby it may be attached to the casing of a well and having a plurality of passages, some of which are in vertical alignment and adapted to permit the passage of the well drilling cable and tools therethrough, and a valve member rotatably mounted on said body and constituting means for restraining the flow of fluid through said body while the drilling cable extends through the said vertically aligned passages of said body and having a deflecting surface serving to change the direction of flow of fluid impinging thereagainst and 130

- being adapted to permit the well drilling tools to pass through said body, said deflecting surface being adapted to occupy a position in which it inclines continuously with- 5 out reversal of direction from one of said vertically alined passages toward another of said passages in said body and being adapted to deflect the fluid impinging thereagainst directly into said last named passage, and 10 said valve member being adapted to occupy a position permitting the well drilling tools to pass through said vertically alined passages while permitting another of said passages in said body to be in open communica- 15 tion with said vertically alined passages.
2. A casing head involving a body having means whereby it may be connected to the casing of a well and having a plurality of passages, some of which are in vertical alinement and adapted to permit the passage of the well drilling cable and tools therethrough, and a plug valve member rotatably mounted on said body and adapted to permit the passage of the well drilling tools and 20 having a curved deflecting surface which extends at an angle to the axis of rotation of said valve and which constitutes means for changing the direction of flow of fluid impinging thereagainst, said valve member 25 constituting means for restraining the flow of fluid through said body and being movable to a position in which said deflecting surface has a direction of curvature extending from one of said passages toward an- 30 other of said passages, and said valve member and body being formed to permit said valve member to restrain the flow of fluid through said body while the drilling cable extends through said body.
3. A casing head involving a body having a plurality of passages therein, some of which are in vertical alinement and adapted to permit the passage of the well drilling cable and tools therethrough, and a plug 35 valve rotatably mounted on said body and having an inclined deflecting surface ex- 40 tends at an angle to the axis of rotation of said valve and which is adapted to change the direction of flow of fluid impinging thereagainst, said valve member being adapted to be rotated to a position in which the said deflecting surface inclines from a vertically opening passage in said body to- 45 ward a laterally opening passage in said body to thereby direct the flow of fluid to- 50 ward said laterally opening passage and being also adapted to occupy a position per- 55 mitting the well drilling cable and tools to pass through said vertically alined passages while permitting another of said passages in said body to be in open communica- 60 tion with said vertically alined passages.
4. A casing head involving a body having a plurality of angularly disposed passages therein some of which are in vertical aline- 65
- ment and adapted to permit the passage of the well drilling cable and tools therethrough, and a plug valve rotatably mounted on said body and affording communication through its end with a laterally opening passage in said body and formed on its interior with a cylindrically curved deflecting sur- 70 face which extends at an angle to the axis of rotation of said valve and which is adapted to change the direction of flow of fluid impinging thereagainst, said valve member constituting means for restraining the flow of fluid through said body and being adapted to occupy a piston in which the direction of curvature of said cylindrical surface ex- 75 tends from one of said vertically alined passages toward said laterally opening passage and being also adapted to occupy a position in which said vertically alined passages and said laterally opening passage are simul- 80 taneously in open relation.
5. A casing head having a body involving a laterally extending passage and a plurality of vertically extending passages adapted to permit the passage of the well drilling cable 85 and tools therethrough, and a plug valve mounted on said body and adapted to control the flow of fluid through said passages, said plug valve being rotatable on an axis passing through said laterally extending 90 passage and being provided with a recess adapted to receive the drilling cable when said valve is moved to restrain the flow of fluid through said body.
6. A casing head having a body involving a laterally extending passage and a plurality of vertically extending passages adapted to 95 permit the passage of the well drilling cable and tools therethrough, and a valve member mounted on said body and adapted to control the flow of fluid through said passages, said valve member being rotatable on an axis extending in the direction of said lateral passage and having a curved deflecting sur- 100 face extending at an angle to the axis of rotation of said valve which is adapted to change the direction of flow of fluid impinging thereagainst, and said deflecting surface being adapted to occupy a position in alinement with said vertically extending passages 105 in which it has a direction of curvature extending from one of said vertically extending passages toward said laterally extending passage.
7. A casing head involving a body mem- 110 ber having vertically extending passages adapted to permit the passage of well drilling cable and tools therethrough and having a laterally extending passage communicat- 115 ing with said vertical passages, and a ro- 120 tatable valve member mounted on said body and adapted to control the flow of fluid through said body, one of said members being provided with a recess which is adapted to receive a drilling cable when said valve 125
- 130

is turned to check the flow of fluid, and said valve member having an opening through its side permitting the valve member to check the flow of fluid while engaging one side 5 only of the drilling cable.

8. A casing head involving a body having a laterally opening passage and also having a plurality of vertically aligned passages which are adapted to permit the passage of 10 the well drilling cable and tools therethrough, and a rotatable valve member which is adapted to control the flow of fluid through said laterally opening passage, said valve member being adapted to occupy 15 a position closing communication between said vertically aligned passages while the said laterally opening passage is in open communication with one of said vertically aligned passages, and said body and said valve member being adapted to receive a drilling cable 20 between them when said valve is moved to check the flow of fluid through said vertically aligned passages while the drilling tools are in the well, said valve member being 25 adapted to engage one side only of the drilling cable when closing communication between said vertically aligned passages while the drilling tools are in the well.

9. A casing head involving a body having 30 a laterally extending passage and a plurality of vertically extending passages therein which are adapted to permit the passage of the well drilling cable and tools therethrough, a cylindrically curved valve member 35 mounted on said body, said body being provided adjacent to said laterally extending passage with a shoulder forming a seat adapted to limit axial movement of said valve, and said valve being rotatable on an 40 axis coinciding with the axis of said laterally extending passage and having an end-bearing coacting with said shoulder, and a stuffing box secured to said body, said valve member having a stem which passes through 45 said stuffing box and the outer end whereof is formed to receive means whereby said valve member may be rotated.

10. A casing head involving a body member having a plurality of vertically aligned 50 passages adapted to permit the passage of the well drilling cable and tools therethrough and also having a laterally opening passage, and a valve member rotatably mounted on said body to turn on an axis 55 coinciding with the axis of one of said passages, said valve member having a curved deflecting surface which extends at an angle to the axis of rotation of said valve and which is adapted to occupy a position in 60 alinement with said vertically extending passages to thereby change the direction of flow of fluid impinging thereagainst and direct it into said laterally opening passage, and one of said members having a recess 65 which is adapted to receive a drilling cable

when said valve member is rotated to check the flow of fluid through one of said passages.

11. A casing head involving a body having therein a laterally extending passage 70 and having vertically extending passages adapted to permit the passage of the well drilling cable and tools therethrough, a valve member rotatably mounted in said body and having a stem whereby it may be 75 rotated on an axis extending through said laterally extending passage, and a stuffing box secured to said body and through which the stem of said valve passes, said valve being formed with a curved deflecting surface 80 having its axis of curvature extending at an angle to the axis of rotation of said valve and being adapted to occupy a position in alinement with said vertically extending passages to thereby deflect fluid impinging thereagainst toward said laterally extending passage and being also formed with a recess which is adapted to receive a drilling cable when said valve is actuated 85 to check the flow of the fluid. 90

12. A casing head involving a body member having vertically aligned passages which are adapted to permit the passage of the well drilling cable and tools therethrough 95 and also having a laterally opening passage communicating with said vertically aligned passages, and a valve member mounted to turn in said body and adapted to occupy a position restraining the flow of fluid through said vertically aligned passages and also adapted to occupy a position permitting the passage of the well drilling tools, said valve member having but a single opening through its side, and said body member and valve member being adapted to receive 100 a drilling cable between them when said valve is moved to close communication between said vertically aligned passages while the drilling tools are in the well. 105

13. A casing head involving a body member having vertically aligned passages which are adapted to permit the passage of the well drilling cable and tools therethrough 110 and also having a laterally opening passage communicating with said vertically aligned passages, and a valve member mounted to turn in said body and adapted when in one position to restrain the flow of fluid through said body and when in another position to cause the fluid to flow through said laterally opening passage, one of said members being provided with a recess adapted to receive the drilling cable when said valve occupies the position for restraining the flow of fluid through said body, said valve member having an opening through its side permitting it when in said last named position to engage one side only of the drilling cable. 115

14. A casing head involving a body member having a plurality of vertically aligned 120

125

130

- passages which are adapted to permit the passage of the well drilling cable and tools therethrough and also having a laterally opening passage communicating with said 5 vertically aligned passages, and a valve member mounted to turn in said body and adapted to restrain the flow of fluid through said body, said valve member being adapted when in one position to permit the passage 10 of the well drilling cable and tools and being also adapted to occupy a position permitting said laterally opening passage to be in open communication with one only of said vertically aligned passages, and said 15 valve member being formed with a continuous deflecting surface which is adapted to occupy a position in alignment with said vertically extending passages and which when so positioned has portions which are 20 respectively tangential to the periphery of said laterally opening passage and to the periphery of that one of the said vertically aligned passages then in communication, and said body member and said valve member 25 being adapted to receive the drilling cable between them when said valve is moved to close communication between said vertically aligned passages while the drilling tools are in the well.
- 30 15. A casing head involving a body member having a plurality of vertically aligned passages adapted to permit the passage of the well drilling cable and tools therethrough and also having a laterally open- 35 ing passage and a rotatable plug valve which is adapted to occupy a position permitting the passage of the well drilling tools and which is also adapted to restrain the flow of fluid through said casing head and to
- close communication between said vertically aligned passages while permitting said laterally opening passage to be in open communication with one of said vertically aligned passages, said body being formed on its interior with inwardly projecting ribs forming bearings for the said plug, some of said ribs respectively surrounding the inner ends of said vertically aligned passages and engaging the said valve member to seal their respective openings, and the surface of the 40 45 50 said body member being depressed between said ribs.
16. A casing head involving a body member having vertically aligned passages adapted to permit the passage of the well drilling cable and tools therethrough and also having a laterally opening passage, and a valve member mounted in said body member and movable with respect thereto, said members being adapted to receive a drilling cable 55 between them when said valve is moved to restrain the flow of fluid through the casing head while the drilling tools are in the well, and said valve member having an opening through its side permitting it to engage one 60 side only of the drilling cable as said valve is moved to restrain the flow of fluid through the casing head while the drilling tools are in the well, and said valve member being adapted to close communication between 65 either of said vertically aligned passages and the interior of the said body member.

In testimony whereof I affix my signature in presence of two witnesses.

ALFRED G. HEGGEM.
